UNITED STATES PATENT OFFICE.

JULIAN KENNEDY, OF PITTSBURG, PENNSYLVANIA.

BOSH-PLATE.

SPECIFICATION forming part of Letters Patent No. 678,785, dated July 16, 1901.

Application filed September 11, 1900. Serial No. 29,643. (No model.)

To all whom it may concern:

Be it known that I, JULIAN KENNEDY, of Pittsburgh, in the county of Allegheny and State of Pennsylvania, have invented a new and useful Improvement in Bosh-Plates, of which the following is a full, clear, and exact description, reference being had to the accompanying drawings, forming part of this specification, in which—

10 Figure 1 is a partial vertical section showing a blast-furnace provided with my improved bosh-plates. Fig. 2 is a broken side elevation of the same; and Figs. 3 and 4 are views similar to Figs. 1 and 2, respectively, 15 showing my preferred form of arranging the plates.

My invention relates to the cooling-plates employed in the boshes of blast-furnaces, and is designed to so improve their construction 20 and arrangement that they will be held firmly in place even when the inner part of the wall is eaten away around them and so that the bosh-walls may be made much thinner than was heretofore possible. To that end the in-

25 vention consists in securing the outer protruding portion of the bosh-plate to the furnace preferably by bolting it to one of the encircling bands commonly used in this part of the furnace.

30 In the drawings, referring to the form of Figs. 1 and 2, 2 represents the bosh-wall of a blast-furnace, having its brickwork provided with encircling bands 3, which are arranged in step fashion, as shown. The cool- 35 ing bosh-plates 4, which may be of any de- sired form and size, are provided with depend- ing lugs or flanges 5, having strengthening- ribs 6, these lugs being bolted to the bands, as shown. Each bosh-plate is also preferably

40 provided with an upper outward extension having an upward flange or lip 7, which will fit against the lower portion of the next suc- ceeding band above it. The bosh-plates are thus securely held in position and will be so 45 retained even where the wall is eaten away. The strengthening-ribs may be provided with a hole 8 for the insertion of a hook to be used in withdrawing the plates.

In the form of Figs. 3 and 4 the bosh-plates

4' are substantially the same as in the previous form, but are spaced apart at their ends to allow the introduction of spacing-plates 9, which carry the strains between the bands, and thus relieve the bosh-plates themselves. I prefer to use this latter construction, since 55 there is less danger of breaking the bosh-plates and they need not be made as strong as in the first form.

In using the plates they may be built into the bosh-wall in the usual manner, but are 60 fastened to the bands in the manner shown.

The advantages of the invention are obvi- 65 ous, since the bosh-walls may be made much thinner than was formerly possible, and the plates will be prevented from tilting or drop- ping down, even where the wall is eaten away around it. Liability to accident is thus largely avoided.

Many variations may be made in the form of the bosh-plate and its cooling-passages and 70 connections without departing from my in- vention.

I claim—

1. A cooling-plate having mechanism for fastening it to the band of a blast-furnace, 75 said mechanism being arranged to fit against the outer portion of the band and allow re- moval of the cooling-plate and its securing mechanism, without disturbing said band; substantially as described.

2. A cooling-plate having lateral lugs or projections and means for bolting them to the furnace-band; substantially as described.

3. A bosh-plate having an upper projection arranged to fit against a furnace-band, and a 85 lower portion having means for securing it to another furnace-band; substantially as de- scribed.

4. A blast-furnace having encircling bands and provided with a cooling-plate located be- 90 tween the lines of the bands and secured to them by mechanism arranged to allow re- moval without disturbing the bands; substan- tially as described.

5. A blast-furnace having its bosh provided 95 with encircling bands arranged in step fash- ion, and bosh-plates having their outer por- tions secured to said bands, said plates being

arranged for removal without disturbing the furnace-bands; substantially as described.

6. A blast-furnace having an encircling band, and a cooling-plate secured to the band by means exterior thereto; substantially as described.

7. A blast-furnace having its bosh provided with encircling bands, spacers extending ver-

tically between them, and cooling-plates secured to the bands; substantially as described. 10

In testimony whereof I have hereunto set my hand.

JULIAN KENNEDY.
